UNITED STATES PATENT OFFICE

GENTRY CASH, OF WHITING, INDIANA, ASSIGNOR TO STANDARD OIL COMPANY, OF WHITING, INDIANA, A CORPORATION OF INDIANA

METHOD AND APPARATUS FOR COKING TARS AND HYDROCARBON OIL RESIDUES

Application filed May 12, 1928. Serial No. 277,334.

This invention relates to the coking of tars and particularly hydrocarbon oil residues.

The invention will readily be understood 5 from the following description in conjunction with the accompanying drawings, in which:

Figure 1 is a sectional elevation of a suitable apparatus for coking such tars and residues;

Fig. 2 is a partial section on the line 2 of Fig. 1; and

Fig. 3 is a detail showing the arrangement of gears whereby rotation of the rolls at different speeds is effected.

Referring to the drawings, 10 is a suitable chamber, preferably well insulated to prevent escape of heat therefrom. Within the chamber 10 are located in superimposed relation a plurality of rolls 11. Said rolls are preferably so spaced that they are in light contact when hot. They are provided with hollow trunnions 12 which are provided with water cooled bearings 13 on the chamber 10. Said trunnions 12 are provided with suitable gears 14 interconnected by idling gears 15 so that the rolls rotate in the same direction. Thus, at their points of contact the peripheries of the rolls move in opposite directions 20 with a rubbing contact which effectively prevents accumulation of solid material.

Suitable means are provided whereby the rolls 11 are brought to a suitable temperature for the coking of the tar. For example, gas or liquid fuel may be admitted by nozzles 16 which are arranged to draw air for their combustion into the rolls 11. The combustion gases emerge by the opposite trunnions and may suitably pass into conduits 17 whereby they are conveyed to a suitable flue. If desired, the combustion gases may be passed from one roll to the other, for example, by conduit 18.

To facilitate the general downward travel 45 of the residuum the surfaces of the various rolls 11 are roughened, for example, by shallow longitudinal grooving shown diagrammatically at 24.

At its upper end the chamber 10 is provided 50 with suitable vapor outlets 19 for withdraw-

ing vapors resulting from the coking of the tars. Suitable distributing means 20 are provided for supplying tar to the uppermost roll 11. At its bottom the chamber 10 is provided with an outlet 21 for the withdrawal 55 of coke. Said outlet may suitably be controlled by a rotary valve 22. A brush or scraper 23 is preferably provided adjacent the lowermost roll 11 for the purpose of removing powdered coke therefrom.

In operation, the rolls 11 are heated so as to bring the uppermost roll to a temperature of at least 800° F., and the temperature of the succeeding rolls to progressively higher temperatures. The lowermost roll may be 60 suitably maintained at a temperature of about 1000 to 1200° F. The residue to be coked is received directly from the last still of a battery or may be preheated by any suitable means to a temperature of about 800° F. 65 Such residue is flowed uniformly onto the top roll and the rolls are rotated at a speed which is adapted to remove coke formed sufficiently rapidly to permit the coking operation to proceed in a rapid and economical manner. For 70 example, with rolls of a diameter of two feet, the uppermost may suitably rotate at between 1 and 5 revolutions per minute. The succeeding rolls should rotate somewhat faster, for example, each roll should rotate 75 about 10% faster than the roll immediately above. The vapors are removed continuously by the conduit 19 and the coke which is crushed and removed from the cylinders is withdrawn by pipe 21 either continuously or 80 intermittently.

Although the present invention has been described in connection with the details of a specific embodiment thereof, it must be understood that such details are not intended 85 to be limitative on the scope of the invention except in so far as set forth in the accompanying claims.

I claim:

1. An apparatus for coking tars comprising 95 a chamber, a plurality of rolls mounted therein adjacent to each other and adapted upon rotation thereof to crush therebetween any coke deposited upon their surfaces, means for rotating said rolls at differential 100

speeds, means for heating said rolls to a temperature sufficient to coke tar, means for supplying a coating of tar to be coked to at least one of said rolls, a vapor outlet from said chamber, and means for withdrawing coke from said chamber.

10 2. An apparatus for coking tars comprising a chamber, a plurality of rolls mounted therein and adapted upon rotation to crush therebetween any coke deposited upon their exterior curved surfaces, means for interiorly heating said rolls to a temperature sufficient to coke tar, means for rotating said rolls in the same direction, means
15 for supplying to the exterior surfaces of the rolls a coating of tar to be coked, a vapor outlet from said chamber, and means for withdrawing coke from said chamber.

3. An apparatus for coking tars comprising a chamber, a plurality of rolls mounted therein and adapted to crush solid matter therebetween, means for interiorly heating said rolls to coking temperature, means for rotating said rolls at differential speeds, a vapor outlet from said chamber and means for withdrawing coke from said chamber.

4. An apparatus for coking tars comprising a chamber, a plurality of rolls mounted therein and adapted to crush solid matter therebetween, means for interiorly heating said rolls to coking temperature, means for rotating said rolls in the same direction and at different speeds, a vapor outlet from said chamber and means for withdrawing coke from said chamber.

5. The method of coking heavy viscous liquid petroleum residues which comprises applying said residues to a series of adjacent rolls, interiorly heating said rolls to a temperature sufficient to coke the residue on said rolls causing the residue to coke upon the rolls, and rotating said rolls at different speeds to cause any coke deposited upon the rolls to be pressed therebetween and removed therefrom.

40 therewith.

6. The method of coking heavy viscous liquid petroleum residues which comprises applying said residues to a series of adjacent rolls, interiorly heating said rolls to a 50 temperature sufficient to coke the residue on said rolls, causing the residue to coke upon the rolls, and rotating said rolls in the same direction at different speeds to cause any coke deposited upon the rolls to be pressed 55 therebetween and removed therefrom.

58 therebetween and removed therefrom.

7. The method of continuously coking
heavy viscous liquid petroleum residues
which comprises applying the residues while
at a temperature of at least 800° F. to the
60 outer surfaces of a pair of rolls set closely
together and adapted to crush solid matter
passing therebetween, heating the rolls to
a temperature between 800 and 1200° F.,
causing the residue on the rolls to coke,
65 rotating the rolls so as to crush any coke

formed thereon, and removing the crushed coke from said rolls.

8. The method of continuously coking heavy viscous liquid petroleum residues which comprises applying the residues while at a temperature of at least 800° F. to the outer surfaces of a pair of rolls set closely together and adapted to crush solid matter passing therebetween, interiorly heating the rolls to a temperature between 800 to 1200° F., causing the residue on the rolls to coke, rotating the rolls so as to crush any coke formed thereon, and removing the crushed coke from said rolls.

9. The method of coking petroleum tar which comprises supplying the tar to the outer surfaces of a pair of rolls set closely together and adapted to crush solid matter passing therebetween, heating the rolls to a temperature sufficient to coke the tar thereon, causing the tar supplied to the rolls to coke, and rotating the rolls to cause the layers of coke thereon to be crushed and removed from the rolls. 80 83

10. The method of coking petroleum tar which comprises supplying the tar to the outer surfaces of a pair of rolls set closely together and adapted to crush solid matter passing therebetween, interiorly heating the rolls to a temperature sufficient to coke the tar thereon, causing the tar supplied to the rolls to coke, and rotating the rolls in the same direction to cause the layers of coke thereon to be crushed and removed from the rolls. 90 95 100

In testimony whereof I have hereunto set my hand and seal this 20th day of April, 1928.

GENTRY CASH.
